UNITED STATES PATENT OFFICE.

JOHANN ROSENTHAL, OF FRANKFORT-ON-THE-ODER, GERMANY, ASSIGNOR TO UNITED SHOE MACHINERY CORPORATION, OF PATERSON, NEW JERSEY, A CORPORATION OF NEW JERSEY.

MACHINE FOR FOLDING EDGES OF SHEET MATERIAL.

Application filed November 30, 1927, Serial No. 236,742, and in Germany March 23, 1925.

The present invention relates to a machine for folding the edges of leather or of other sheet material in a step by step operation. The machine is fitted with folding means 5 which at first bend the edge up at an angle of ninety degrees, then fold it over, and finally press it down. After every such operation the material is fed forwards.

The object of the invention is a special 10 arrangement of these means in order to obtain folded edges of a perfectly uniform outline even where they show curvatures of very small radii. With this object in view the material worked upon is so held in place 15 that it cannot spread or yield in the direction of feed nor in a transverse direction beyond the outline desired during the folding over operation, the yielding of the edge-material in these directions being the main 20 cause of the distortion of the folded-edge otherwise encountered. The yielding of the edge material in the said directions during the folding operation is prevented by causing the bender and the presser to remain in 25 their working position while the upwardly bent edge is folded over. In this position of parts the presser and the bender prevent the work from yielding or spreading in the said two directions while being folded. To this 30 end the folder performs a twofold movement viz, a movement independent of the bender in a direction parallel to the sheet material and a common movement with the bender in a direction vertical to the sheet 35 material.

A simple embodiment of the invention will now be described with reference to the accompanying drawings, in which

Fig. 1 shows a front elevation, and

Fig. 2 shows an end elevation of the machine, several parts being omitted for the sake of clearness.

Fig. 3 shows the upper feeding finger and its driving parts on an enlarged scale.

Fig. 4 is a cross section along the line I—I of Fig. 3.

Fig. 5 illustrates some of the cooperating instrumentalities.

Fig. 6 is a view of the edge-guide.

Fig. 7 is a cross-section through the working instrumentalities somewhat above and parallel to the work-table.

Fig. 8 is a vertical cross-section along the line II—II of Fig. 1.

The feeding fingers 1 and 2 are carried 55 by the frame 16 which has the form of a horse-shoe and swings about the vertical axis 17. The feeding finger 1 is mounted on the block 15 which is supported by the spring 12 in a vertical slot of the frame 16. 60

The upper end 23 of the finger 1 is adapted to be acted upon by the arm 24 of the shaft 25 so that the finger 1 is lowered.

In the lower arm of the frame 16 is arranged the vertically slideable feeding finger 65 2. It is supported by a spring 37 on the crank arm 26 of the shaft 27. The swinging shaft 27 compresses the spring and urges 70 yieldingly the feed finger 2 upwardly. At the rear-ends of the shafts 25 and 27 there 75 are provided cranks connected to each other by appropriate rods and the two-armed lever 28 pivotally mounted on the stud 29 of the machine-frame. A cam 38 keyed to the driving shaft 32 swings by the means shown 80 in Fig. 8 the stud 29 and moves the two fingers 1 and 2 against each other. With the fingers 1 and 2 closed the swinging frame 16 feeds the work. The frame 16 is swung 85 about the vertical shaft 17 by means of the shaft 19, the crank 19' and the connecting bar 18, see Fig. 2. The swinging movement of the shaft 19 is derived from a cam 42 of the shaft 32 by means of the lever 41, see Fig. 2.

The feeding finger 1 has at its lower end 90 a lateral prolongation 39 about which the edge of the material is at first bent upwardly by the bender 3 after which it is laid down by the folder 4.

The bender 3 is fastened to the slide 22 moved by the lever 30, and the shaft 31, oscillated by suitable means by the cam-shaft 32. The folder 4 is fastened to the vertical slide 20 moving in the horizontal 95 slide 21. While the bender 3 and folder 4 are operating the material is held by the hold-down 5 on the table 9. At the same time the hammer 6 presses upon the margin already folded over. The hold-down 5 is 100 moved upwards by the cam 35 and the lever 34 and is held in its lower position by a spring 40. The hammer 6 is arranged in a similar manner, it is raised by a lever 45. The hold-down 5 may also be lifted by the 105 hand-lever 13 engaging underneath the lever 34. The spring 12 carrying the feeding finger 1 is fastened to the hold-down 5 to be

simultaneously lifted therewith. In front of the instruments described a plough-like guide 7 for the edge to be folded is fastened to the table 9. This guide is adjustable by means of the screw 36 and forms at the same time a gauge for the width of the fold.

The operation of the machine is as follows:

While the machine is at rest the feeding fingers 1, 2 are apart from each other. The attendant lifts with his left hand by means of the handle 13 the hold-down 5 and introduces with his right hand the material through the guide 7 underneath the hold down and between the said feeding fingers 1, 2, whereupon he releases the hold-down 5 to clamp the material on the table 9. The cam-shaft 32 is then rotated either by the handle 33 or by a motor-drive. The rotating shaft raises the bender 3 which bends the edge of the material up about the prolongation 39 of the finger 1. Now the folder 4 in the path of which the bender lies lowers to come into contact with the bender 3. While the folder proceeds laterally in order to lay the upturned edge down onto the body portion of material lying on the table 9 it moves at the same time downward with the folder 3. While the folder and bender are thus operating and while the hold-down 5 is in its low position the hammer 6 presses down in the immediate neighbourhood the part of the edge which has been acted upon in the preceding cycle of operation. Thus the hammer 6 does not allow the part of the margin which is just being folded over to spread or bulge in the direction of the feed, while the bender 3 does not allow it to spread or bulge beyond the desired line of fold. Now the fingers 1 and 2 grip the work-piece and the parts 5 and 6 are lifted to free the material for the feed. The frame 16 swings in the direction of the feed for one step, the hold-down 5 descends again and the hammer 6 lowers to press down the edge already folded. Finally the fingers 1, 2 open and the frame 16 returns, whereupon the described operation repeats.

What I claim is:

1. A folding machine having, in combination, a work support, means for feeding the work intermittently over the support, and mechanism for progressively folding the

margin of the work over the body portion and for pressing the fold, said mechanism comprising a folder movable in a given path and means for engaging the work simultaneously at a previously folded locality and at a locality on the line of fold in the plane of the path of the folder during the time that the folder is operating. 55

2. A folding machine having, in combination, a work support, means for feeding the work intermittently over the support, and means for progressively folding successive portions of the margin over the body portion of the work during the pauses in the intermittent feed and for pressing them into place, said means comprising a bender for bending up the margin, a folder for folding the bent-up margin over the body portion, a presser, and means for causing the presser to engage a folded over portion of the margin and the bender to engage the base of the bent-up margin at the line of fold in the plane of the path of the folder during the time that the folder is folding the bent-up margin over the body portion of the work. 75

3. A folding machine having, in combination, a work support, means for intermittently feeding the work over the support, a bender, means for moving the bender upward to bend up the margin of the work, a folder, means for causing the folder to move the bender downward and to fold the bent-up margin over the body portion of the work, and means for pressing the fold. 80

4. A folding machine having, in combination, a work support, means for intermittently feeding the work over the support, a bender, means for moving the bender upward to bend up the margin of the work, a folder, means for causing the folder to move the bender downward and to fold the bent-up margin over the body portion of the work, and means for pressing the fold, the construction and arrangement being such that, while the folder is folding the margin over the body portion of the work, the presser engages a previously folded-over portion of the margin and the bender engages the edge of the fold at the locality in which the folder is folding a succeeding portion of the margin of the work. 95

In testimony whereof I affix my signature.

JOHANN ROSENTHAL.
